UNITED STATES PATENT OFFICE.

ROBERT MUNN DIXON, OF EAST ORANGE, NEW JERSEY.

DESIGN FOR A HOSE-CO尤LING MEMBER.

SPECIFICATION forming part of Design No. 29,148, dated August 2, 1898.

Application filed January 27, 1898. Serial No. 668,228. Term of patent 14 years.

To all whom it may concern:

Be it known that I, ROBERT MUNN DIXON, of East Orange, in the county of Essex, State of New Jersey, have invented a certain new

5 and useful Design for Hose-Coupling Members, of which the following is a complete specification, reference being had to the accompanying drawings.

Figure I is a top plan view of a coupling member, showing my design. Fig. II is a side elevation thereof. Fig. III is an end view of the subject-matter of Fig. I.

As shown in the drawings, the leading or material features of my design consist of a 15 body part 1, whose general external contour is that of a cube, a shank 2, inclined upwardly from the body part, and a lateral extension 3 upon one side of the body part. The body part is provided upon one side with 20 a projection 4. The extension 3 is provided

upon one side with a shoulder 5 and upon the same side with a projection 6. The shank is provided with an annulus 7 and a bulbous head 8.

9 indicates a bore which extends through 25 the shank 2 and the body part 1.

The extension 3 is provided with a web 10, the body part 1 with a projection 11, and the shank 2 with parallel perforated lugs 12.

Having described my invention, what I 30 claim as new, and desire to secure by Letters Patent, is—

The design for a hose-coupling member as herein described and shown.

In testimony of all which I have hereunto 35 subscribed my name.

ROBERT MUNN DIXON.
